UNITED STATES PATENT OFFICE.

ORIN W. SADLER, JR., OF BELLE VERNON, PENNSYLVANIA.

APPARATUS FOR POLISHING METAL ARTICLES.

1,418,677.

Specification of Letters Patent. Patented June 6, 1922.

Application filed January 31, 1921. Serial No. 441,345.

To all whom it may concern:

Be it known that I, ORIN W. SADLER, Jr., a citizen of the United States, and resident of Belle Vernon, in the county of Fayette and State of Pennsylvania, have invented a new and useful Improvement in Apparatus for Polishing Metal Articles; and I do hereby declare the following to be a full, clear, and exact description thereof.

10 My invention relates to apparatus for polishing or grinding metal articles. While the invention has particular advantages in connection with the polishing or grinding of dies for drawing tubing and like circular articles, its application is not, in any sense, limited to such articles.

The object of my invention is to provide a simple and effective way of polishing or grinding the working faces of dies or like articles in which the abrasive acts on the working face of the die and in substantially the same direction as the flow of the work in cold drawing, so that there is less tendency to mar or scratch the work. Where 20 the polishing is done in a circumferential direction, as in the old process, there is a tendency to leave the surface grooved, so that where the tube is being drawn through the die it is subjected to varying pressures, 25 concentrating the pressure on the high spots and thereby increasing the tendency to "gall" or abrade both die and tube, whereas as by my method the face of the die is brought nearer and nearer to a regular curve 30 and pressure between the tube and die is thereby more regularly distributed.

With these and other objects in view, my invention comprises the novel features hereinafter set forth and claimed.

40 In the drawings, Fig. 1 is a vertical side elevation of my invention partly in section; Fig. 2 is a front view of the abrading belt, showing the different positions of different sized work for obtaining proper angle of 45 contact; Fig. 3 is a rear view of a portion of the machine showing the driving mechanism; Fig. 4 is an enlarged plan view of the die and holder; and Fig. 5 shows a modified form of my invention.

50 In the drawing, the numeral 2 designates a suitable frame upon which is mounted the motor 3. On one end of the motor-shaft 4 is the pulley 5 around which the belt 6 passes, said belt also passing around the 55 pulley 7 on the shaft 8. On the shaft 8 is the pinion 8^a which meshes with the pinion

10 on the shaft 11, said shaft being carried by the links 11^a and 11^b. The pinion 10 meshes with the gear-wheel 12 on the shaft 13. The shaft 13 is journaled in suitable 60 bearings in the frame 18 and at the outer end of said shaft is a beveled friction wheel 14 which engages the beveled face 15 of the rotary-holder 16. Additional idle beveled friction-wheels 17 are provided, mounted in 65 the circular portion 18^a of the frame 18.

The rotary-holder 16 is stepped to form seats 19 of varying diameter to provide for the seating of dies of different diameters. The die 20, illustrated, is of such diameter 70 as to fit in the uppermost seat of the rotary-holder, and said die is of the ordinary type used in the cold drawing of seamless tubing having the wide bell-mouth 21 on the intake side and the narrower or contracted 75 outlet 22.

The frame 18 is movable up and down on the frame 2, suitable guides 23 being provided, and connected to said frame is the screw-bar 24 which is moved up and down 80 by the hand-wheel 25 to provide for the adjustment of the frame 18 for the purpose more fully hereinafter set forth.

Mounted on the shaft 4 is the pulley 26 around which the belt 27 passes, said belt 85 also passing around the pulley 28 of smaller diameter on the shaft 29. The shaft 29 is mounted in bearings 30 which are slideable up and down in the guides 31 for purposes of adjustment to hold the belt 27 at the 90 proper tautness, and for this purpose a link 32 is connected to the lug 33 on the bearing 30, and said link is connected by the strap 34 to the lever 35, adapted to engage the toothed quadrant 36 in the ordinary manner. 95

The belt 27 may be made of any suitable abrasive coated material such as emery cloth. The width of this belt may vary according to requirements.

Where a die, like 20, is to be polished or 100 ground, the die is placed on the rotary holder 16 with the abrading belt 27 passing through the same and bearing against the interior of the die at opposite points thereof, as indicated in full lines, Fig. 2, the 105 frame 18 having been previously adjusted so that the belt will have the proper angle of contact to evenly polish or grind the faces of the die to be operated on. This angle may be varied by raising or lowering the frame 110 18. The motor 3 is started, and through the connections described a rotary movement is

given to the holder 16 by the driving action of the friction wheel 14, and the die 20 carried thereby is rotated. At the same time the abrasive belt 27 is driven, and as the belt 5 moves in opposite directions at the points of contact the tendency of the upward movement of the belt to dislodge the die from its seat will be counteracted by the downward movement of the belt, so that the die 10 remains securely seated during the polishing or grinding operation without the employment of any means for clamping the said die in position. The flexibility of the belt permits it to conform to the curve of the die, 15 and as the die is rotating and the belt moving all points on the die are subjected to the same polishing or grinding action, so that there is no variation of pressure to cause any scratching or marring of the die, and 20 the fact that the abrasive cuts the working face of the die in substantially the same direction, as the flow of the work causes less tendency to scratch the work when the die is in use.

25 Where a die of lesser angle is to be ground, as shown in dotted lines, Fig. 2, the die is lowered, bringing the belt into closer relation, and for this reason it is desirable to have the pulley 28 of smaller diameter than 30 the pulley 26. If, however, it is desired to polish or grind a double ended or double bell-mouth die, the result is accomplished by increasing the diameter of the lower pulley.

35 In Fig. 5 I have illustrated my invention in connection with a crossed belt, and by crossing the belt a sharp edge on the lower or cutting edge of the die is secured, as in the case of a circular punching die, and as 40 the hole is kept larger at one end than at the other a proper amount of "relief" is afforded. As a consequence the machine may be used, not only for polishing punching dies of circular and other forms, but also for 45 sharpening them. Inasmuch as the abrasive action is quite rapid the machine may be used to shape or enlarge the hole in dies.

Again where a die is out of round, or 50 slightly oval, it may be brought back to a more nearly circular shape by retarding the travel of the holder while the belt is in contact with the narrower diameter. This may be accomplished by exerting a slight pressure against the rotation of the holder with 55 the hand, or mechanical means may be provided for this purpose.

It will be apparent that there are many 60 applications of my invention, and I do not wish to limit it in any way to the polishing of drawing or punching dies, such as referred to specifically, but wish to include within its scope any practical use to which it may be applied.

What I claim is:

1. In a machine of the character described, a rotary work-support having an opening, an abrasive belt passing through said opening, means for driving said belt, means for adjusting said belt and said support, the one with relation to the other, whereby the angle of contact of said belt with the work may be varied, and means for rotating said support. 65

2. In a machine of the character described, the combination of a rotary work-support having an opening, an abrasive belt passing through said opening adapted to engage the work resting on said support at opposite points thereon, means for moving the belt at one point of contact in an opposite direction to the belt at the other point of contact, and means for rotating said support. 75

3. In a machine of the character described, the combination of a work-support having an opening, an endless belt passing through said opening, means for moving said work-support longitudinally of said belt, whereby the angle of contact of said belt with the work may be varied, and means 80 for rotating the said support. 85

4. In a machine of the character described, the combination of a work-support having an opening, an endless cross-belt of abrasive material passing through said opening arranged to engage the work, and means 90 for rotating said support. 95

5. In a machine of the character described, the combination of a work-support having an opening, an endless belt of abrasive material passing through said opening, and means for rotating said support. 100

6. In a machine of the character described, a work-support having an opening, an abrasive belt passing through said opening arranged to engage the work at opposite points, means for driving said belt, and means for adjusting said belt and said support, one with relation to the other, whereby the angle of contact of said belt with the work at opposite points may be varied. 105

7. In a machine of the character described, the combination of a work-support having an opening, an endless belt passing through said opening engaging the work at opposite points, and means for moving said work-support longitudinally of said belt, whereby the angle of contact of said belt with the work at opposite points may be varied. 115

In testimony whereof, I, the said ORIN W. SADLER, Jr., have hereunto set my hand. 120
